PUNCH PRESS FRAME

Richard F. Gallagher, San Jose, Calif.

Application September 16, 1957, Serial No. 47,757

Term of patent 3½ years

(Cl. D63—1)

Fig. 1 is a side elevational view of a punch press frame embodying my new design.

Fig. 2 is a top plan view of the punch press frame of Fig. 1; and

Fig. 3 is a front elevational view thereof as seen from the left in Fig. 1.

The opposite side of the frame is substantially the same in appearance as the side shown.

I claim:

The ornamental design for a punch press frame, as shown and described.
